UNITED STATES PATENT OFFICE.

JOHN W. McMAHAN AND EDWIN S. WHITTEMORE, OF HUNTINGDALE, MISSOURI, ASSIGNEES TO THEMSELVES AND HULL HICKMAN PAGE, OF SAME PLACE.

CORN-PLANTER AND CHECK-ROWER.

SPECIFICATION forming part of Letters Patent No. 372,480, dated November 1, 1887.

Application filed May 3, 1887. Serial No. 236,960. (No model.)

To all whom it may concern:

Be it known that we, JOHN WESLEY McMAHAN and EDWIN STANTON WHITTEMORE, both of Huntingdale, in the county of Henry and State of Missouri, have invented a new and Improved Corn-Planter and Check-Rower, of which the following is a full, clear, and exact description.

The object of our invention is to provide a new and improved corn-planter and check-rower which is simple and durable in construction and very effective in operation.

The invention consists in the construction and arrangement of various parts and details and combinations of the same, as will be fully described hereinafter, and then pointed out in the claim.

Reference is to be had to the accompanying drawings, forming a part of this specification, in which similar letters of reference indicate corresponding parts in all the figures.

Figure 1 is a plan view of our improvement, parts being in section. Fig. 2 is a sectional side elevation of the same on the line *x x* of Fig. 1. Fig. 3 is a vertical cross-sectional elevation of part of our improvement on the line *y y* of Fig. 1. Fig. 4 is a sectional end elevation of part of our improvement on the line *z z*, Fig. 1. Fig. 5 is a sectional side elevation of the same on the line *w w* of Fig. 4. Fig. 6 is a sectional end elevation of the seed-box frames on the line *u u* of Fig. 2, and Fig. 7 is a plan view of one end of the seed-box frame with the seed-box removed.

On the suitably-constructed frame A is secured the axle or shaft B, on the ends of which are mounted loosely the driving-wheels C and C', of which the driving-wheel C is provided on its inner hub with a clutch-wheel, D, adapted to engage a clutch-wheel, E, formed on the hub of the cam-wheel F, mounted loosely on the part B' of the axle B. The cam-wheel F is provided with three projections, F', in its rim, adapted to engage alternately the friction-roller G', mounted on one end of the lever G, fulcrumed on the main frame A, and engaging with its other end the slotted arm H', secured to the bar H, adapted to slide sidewise on top

of the seed-box frame I, pivotally connected with the main frame A.

The two ends H² of the sliding bar H are reduced and slide in suitable grooves formed in the bottom of the seed-boxes K, of suitable size, and held on the outer ends of the seed-box frame I. In the center of the bottom of each seed-box K is pivoted a slide, L, provided with a slot near its outer end, which engages a pin, H³, secured to the top of the reduced part H² of the sliding bar H. In each of the slides L is also formed an aperture, L', adapted to register with a vertical slot, J', formed in the rear end of the plow J, secured to the outer end of the seed-box frame I, directly below the seed-box K. In the slot J' is pivoted the lever N, forked at its upper end, and engaging with this end the pin H⁴, secured to the inside of the reduced part H² of the sliding bar H.

The lever N is so arranged in the slot J' that when its upper end is on one side of the slot J' then the lower end of the lever is at the opposite side of the slot, and when the bar H moves sidewise then the relative positions of the upper and lower ends of the lever N are correspondingly changed from one side of the slot to the other. The sidewise motion of the bar H also imparts a swinging motion to the slides L by means of the pin H³, so that the apertures L' open into the slots J' and deliver grain to said slots from the seed-boxes K. Near the middle of the sliding bar H, and extending downward, is secured a toothed rack, O', meshing into the segmental teeth O', formed on the upper end of the lever O, fulcrumed on the seed-box frame I and extending downward, being pointed at its lower end, which is adapted to mark in line with the respective hills into which the grain has been dropped when the levers N were actuated by the sliding bar H.

On the inside of the cam-wheel F is formed a hub, F², grooved at its rim, which is engaged on its upper side by a semicircularly-grooved rim formed on the disk P, mounted loosely on the part B' of the shaft B. Against the outer face of the disk P presses one end of the spring P', coiled on said part B' of the shaft B, and resting with its other end against the shoulder

formed on the shaft B. This spring P' has a tendency to press the clutch E of the cam-wheel F into contact with the clutch D of the main driving-wheel C. From the face of the disk 5 P project inward two arms, P', pivotally connected by the links Q with the forked end of the lever R, extending upward and being fulcrumed on the main frame A.

The operation is as follows: The operator 10 occupying the seat S, secured to the main frame A, can move the cam-wheel F in and out of contact with the main driving-wheel C by moving the forked lever R sidewise, so that the links Q impart a sliding motion to the disk P, which, 15 by its semicircularly-grooved rim, moves the cam-wheel F sidewise on the part B' of the shaft B. When the cam-wheel F is in clutch-contact with the main driving-wheel C, and the frame is moved forward in the direction of 20 the arrow a', then the main driving-wheel C imparts a rotary motion to the cam-wheel F, which, by its projections F', imparts a sliding motion to the bar H by means of the lever G. As the cam-wheel F is provided with three 25 projections F', it will be seen that for every revolution of the main driving-wheel C said cam-wheel F imparts a sliding motion to the bar H three times. The sidewise sliding motion of the bar H imparts a swinging motion to the 30 slides L by means of the pins H³, and at the same time the bar H imparts a rocking motion, by means of the pins H⁴, to the levers N in the slots J' of the plows J. The levers N stand parallel to each other, and in such a relative 35 position at their upper ends to the apertures L' that the latter drop, on their swinging motion, corn into the slots J' at every sidewise motion of the sliding bar H. The grain dropped into the slots J' is retained in the same by the 40 levers N, and is only delivered to the ground at the next shifting motion of the levers N, imparted to the same by the sliding bar H. Then the grain passed from the seed-boxes into the 45 slots J' by means of the slides L is retained in said slots J' until the next sidewise motion of

the levers N, and then the grain in both slots is dropped simultaneously into the furrows formed by the front end of the plows J. At the same time that this takes place the bar H imparts, by its rack O², an oscillating motion 50 to the lever O, so that the latter forms with its pointed lower end a small furrow in the ground between the two hills in which the grain had been dropped, as above described.

If the operator desires to interrupt the sliding motion of the bar H, thus preventing the seed from dropping into the furrows, he moves the upper end of the lever R outward, whereby the links Q pull on the disk P, which, by its semicircularly-grooved rim, pulls the cam-wheel F inward, whereby the clutch E is disengaged from the clutch D of the main driving-wheel C, and the latter rotates without rotating the cam-wheel F. It will be seen that at the moment the grain is dropped into the 65 furrow from the two seed-boxes K the hills in which the seed has been dropped are marked by the scraping-lever O.

Having thus fully described our invention, we claim as new and desire to secure by Letters 70 Patent—

The combination, with the frame, the drive-wheels, axle, grooved cam-wheel F thereon, provided within the groove with the three projections F, and a clutch mechanism for said 75 cam-wheel, of the horizontally-oscillating lever G, entering the groove of the cam-wheel at its rear end, the transversely-movable slide-operating bar, the pivoted seed-slides L, operated by said bar, the pivoted levers N in the seed-spouts and operated by said bar, the rack O² on the bar, and the vertical pivoted marker O, having teeth on its upper end engaging said rack, substantially as set forth.

JOHN W. McMAHAN.
EDWIN S. WHITTEMORE.
